UNITED STATES PATENT OFFICE.

FRANK R. GREENE, OF CHICAGO, ILLINOIS.

VENDING RECEPACLE.

1,418,560.

Specification of Letters Patent. Patented June 6, 1922.

Application filed March 24, 1919. Serial No. 284,807.

To all whom it may concern:

Be it known that I, FRANK R. GREENE, a citizen of the United States, residing at Chicago, in the county of Cook and State of Illinois, have invented a certain new and useful Improvement in Vending Receptacles, of which the following is a specification.

The object of my invention is to provide a vending receptacle for chewing gum, candies and the like which is adapted to display the articles and to hold them so that the purchaser may help himself. I provide in connection with my invention a coin receiving receptacle which is a part of it and is adapted to be locked.

My invention is illustrated in the accompanying illustration wherein

Fig. 1 is a front elevation with parts cut away.

Fig. 2 is a section along the lines 2—2 of Fig. 1.

Fig. 3 is a section along the lines 3—3 of Fig. 2.

Fig. 4 is a section along the lines 4—4 of Fig. 2.

Fig. 5 is a side elevation showing the modified form of door.

Like parts are indicated by like characters in all the figures.

A is a base having the horizontal front extention A¹ and the downwardly inclined rear extention A². It is supported on the cushion knobs A³.

B is a rear plate of the containing body apertured at B¹ for the removal of coin from the coin receptacle B². B³ is a door to said receptacle adapted to be locked by the lock B⁴.

CC are side plates extending vertically upward and joined at their rearward edges to the back plate B.

D is a curved upper plate joining the side plates and the back plates and apertured at D¹ for the introduction of coin. D² is a hinged hanger by means of which my device may be suspended from a wall, should that be desirable.

EE are parallel vertical partitions dividing the body into a series of compartments adapted to receive and hold the gum or candies. E¹ is a mirror on the front face of the coin receptacle. E²E² are scales marked on the face of my device by means of which the amount of gum or candies in the machine may readily be determined. E³ shows

the scale E² on the side of the partitions instead of on the front of the case. FF are doors mounted on the front of my machine and carried by the spring hinges F¹F¹ and are normally held in the closed position by the springs F². F³F³ are handles on the front of the doors by means of which they may be opened.

G is a cushion in rear of the mirror E¹ and separating it from the front plate G¹ of the coin receptacle.

HH are pieces of gum or candies such as mints and the like in position in my receptacle.

The use and operation of my invention are as follows:

The machine is filled with gum, candies, mints and the like and is placed in some public place, either hung upon the wall or standing upon a counter or some other support. The doors are held normally closed as a protection from moisture and dirt. Any one desiring to purchase from the machines has only to open the door against the slight pressure of the spring and then make his selection from the goods there displayed before placing his coin in the coin receptacle by means of the slot in the top of it. As soon as he releases his hold upon the door it closes and will tend by means of the spring which closes it to keep the gum or candy in the proper place should any of it have been partially dragged out by the purchaser in withdrawing the pieces which he bought.

In some forms I might prefer to manufacture my invention without the doors but the principle of the invention itself would, of course be the same, and although I have shown in my drawings an operative device, still many changes might be made in size, shape and arrangement of parts without departing materially from the spirit of my invention, and I wish, therefore, that my drawings be regarded as in a sense diagrammatic.

I claim:

1. A vending receptacle comprising a base member, a housing projecting from one side thereof, containing a plurality of separate vertically disposed package receiving chambers adapted to hold stacks of superposed packages, the floor of each chamber being downwardly and rearwardly inclined, the housing covered at the top by a curved rigid

- closure, closing the top of each of the package chambers and doors pivoted on the housing wall and yieldingly closing the front side of the chambers.
5. 2. A vending receptacle comprising a base member, a housing projecting from one side thereof, containing a plurality of separate vertically disposed package receiving chambers adapted to hold stacks of superposed packages the floor of each chamber being downwardly and rearwardly inclined, the housing covered at the top by a curved rigid closure, closing the top of each of the package chambers and doors pivoted on the housing wall and yieldingly closing the front side of the chambers, the doors be-
- ing pivoted on the outside of the housing and terminating at points short of the center line of the housing, whereby there is a space between the inner edges of the doors 20 when they are closed, an advertising device mounted on the housing between said doors adapted to be closed at all times and a coin receptacle behind said advertised device.
- In testimony whereof, I affix my signature in the presence of two witnesses this 7th day of March 1919.

FRANK R. GREENE.
